CONTAINER AND LIQUID-TIGHT LINER
THEREFOR

Glenn V. Haven, Minneapolis, Minn.

Application May 4, 1935, Serial No. 19,809

1 Claim. (Cl. 150—48)

My invention has for its object the provision of a simple and highly efficient container having a removable water-tight paper liner for general use in carrying liquid.

5 While the invention is intended for general use, it is especially well adapted for use as a camp pail. The container, when not filled with a liquid, is flat and can be carried in a very small space which is highly important when transporting camp 10 equipment in an automobile, canoe or other vehicle, or when making portages. The liner for the container is formed to fit the container by folding a square piece of waterproof paper when needed, and as will hereinafter appear. Waterproof paper from which the liners are folded is of the proper size and can also be carried in compact form.

To the above end, generally stated, the invention consists of the novel devices and combinations of devices hereinafter described and defined in the claim.

In the accompanying drawing, which illustrates the invention, like characters indicate like parts throughout the several views.

25 Referring to the drawing:

Figs. 1 to 4, inclusive, are perspective views showing successive steps in the process of forming the liner, the completed liner being shown in Fig. 4;

30 Fig. 5 is a perspective view of the container and liner with the sides thereof separated as they will appear when the liner is filled with a liquid, as shown in Fig. 6; and

Fig. 6 is a view in vertical section taken on the 35 line 6—6 of Fig. 5.

Referring first in detail to the container which comprises two duplicate side pieces 1 cut from canvas or other suitable fabric and placed, the one piece upon the other. The top and bottom edges 40 of the side pieces 1 are parallel and the upright edges thereof are in upwardly diverging relation. These side pieces 1 are connected at their bottom and upright edges by stitches 8 and the top edge portion thereof is folded outwardly and downwardly upon itself to form a hem 9 secured in place by stitches 10. Each side piece 1 is provided with a loop-like handle 11, the end portions of which are tucked under the hem 9 and secured to said hem and the side pieces 1 by 45 stitches 12. When the container 1 is not in use its side pieces lie flat, the one upon the other. If necessary when packing the container, the same may be folded or rolled in order to place the same into a more compact space.

50 Referring now in detail to the liner 13 of the container, the same is formed from a single square piece of waterproof paper. The size of the square piece of paper is such that when folded to form the liner, said liner snugly fits in the container and is removably held thereby.

The process of folding the improved liner is as follows: The square piece of paper is first folded upon itself with one corner on the diagonally opposite corner to form a right angle triangle and the paper creased at 14 or, in other words, at 5 the hypotenuse of said triangle, see Fig. 1.

Next, the lower right hand corner section 15 of the triangle 14 is folded upon said triangle in a position in which its point is at the left hand edge of the triangle 14 and with its upper edge 10 parallel to the hypotenuse of the triangle and the paper again creased at 16, as shown in Fig. 2. Next, the partially formed liner is turned over and the lower right hand corner section 17 of the triangle 14 is folded upon said triangle on the opposite side thereof from the corner section 15 and with its upper edge aligned with the upper edge of the corner section 15, see Fig. 3. The paper is again creased at 18. Next, the uppermost pointed section of the triangle 14 is folded 20 outwardly and downwardly onto the corner section 17 and creased over the upper edge of said section 17. Finally, the partially formed liner is turned over and the other upper pointed portion of the triangle 14 is folded outwardly and 25 downwardly onto the corner section 15 to complete the liner, as shown in Fig. 4.

The completed liner is now ready to be placed in the container which not only affords a reinforcement therefor but affords convenient means for carrying the same. The liner may be made from relatively light-weight paper for the reason that the container will hold said liner against undue pressure from liquid in said liner.

Due to the difficulty of keeping a water pail in a clean and sanitary condition when in camp, the above described container and liner will fill a long-felt want for the reason that the liner can be thrown away when the same is empty and a 40 new liner folded and placed in the container, thus keeping the pail clean and in a sanitary condition.

It will of course be understood that the liners may be folded at the time of manufacture in 45 place of folding the same when needed.

What I claim is:

As a new article of manufacture, a container comprising two side pieces cut from fabric, placed the one upon the other and fastened together at 50 their edge portions except at the top thereof, by means of flat seams, a loop-like handle attached to each side piece at the upper edge portion thereof, and a removable liquid tight liner for the container formed by folding a single 55 piece of paper, said liner being held folded by the container with freedom for like opening and closing movements therewith.
